D10-35.

OR D 12,896 EX

DESIGN FOR A WATCH-CASE.

Design No. 12,896, dated April 18, 1882.

UNITED STATES PATENT OFFICE.

HENRY UNTERMEYER, OF NEW YORK, N. Y.

DESIGN FOR A WATCH-CASE.

SPECIFICATION forming part of Design No. 12,896, dated April 18, 1882.

Application filed November 11, 1881. Term of patent 7 years.

To all whom it may concern:

Be it known that I, HENRY UNTERMEYER, of New York, in the county and State of New York, have invented a Design for a Watch-case, of which the following is a specification.

The design consists of a representation of a running horse and jockey and reach of track displayed to occupy the central field of a watch-case and encircled by a frame of dots presenting the appearance of beaded work.

In the accompanying illustration of the design, Figure 1 is a photographic view, showing the front or side of a watch-case. Fig. 2 is a detached view, showing the elements which are claimed.

The leading feature of the design is the horse and jockey with reach of track displayed as shown, the spirited effect of which is enhanced by the circular frame of dots in the nature of beaded work, and other parts of the design, as shown.

The background of the design is in part oc-

cupied by a representation of a "judges' stand," the pointed roof of which is conspicuous, and the lower foreground is occupied by a reach 25 of track, all as shown in the illustrations; but the judges' stand is not of the essence of the design. The upper background may be covered with straight-line engine-turning or other incidental features, to add to the effectiveness 30 of the whole.

What I claim is—

The design for a watch-case, consisting of a running horse and jockey and reach of track displayed to occupy the central field of the 35 case and inclosed by a circular border, substantially as shown and described.

Witness my hand this 5th day of November, A. D. 1881.

HENRY UNTERMEYER.
